SEPARABLE AND ADJUSTABLE
DOOR SUPPORT

Luther D. Lewis, Clover, Va.

Filed Oct. 3, 1958, Ser. No. 765,103

2 Claims. (Cl. 144—296)

This invention relates to tools or jigs for use by carpenters, millwrights, mechanics and the like, and in particular an adjustable stand particularly adapted for supporting a door in such a position that the upper edge is at a comfortable elevation to be worked on for cutting recesses for hinge plates and openings for locks and the like, and the stand is collapsible to facilitate transportation from one job to another or whereby the complete device may be carried in a tool bag or the like.

The purpose of this invention is to provide means for supporting a door, window sash, blind, or the like so that the upper edge is at a comfortable elevation and wherein the door or the like is rigidly held.

In cutting out parts of edges of doors, window sash, blinds, and the like to receive hinge plates, locks, sash cords, and the like the article is placed with one edge on the floor or on a bench and it is necessary for the carpenter to bend over or stand on a step, or the like to remove the material to form a hinge plate, lock, or sash cord opening and as it is necessary to locate such openings, particularly for hinge plates, in accurate positions, working with the edge of a door at a low elevation or in an elevated position requires considerable skill.

The object of this invention is, therefore, to provide means for supporting a door, window sash, blind, or the like whereby the upper edge is located at an elevation that corresponds with the height or size of the carpenter or mechanic using the device.

Another object of the invention is to provide a supporting stand for doors, window sash, blinds, and the like in which the parts are readily adjustable.

Another important object of the invention is to provide a supporting stand for holding a door, window sash, blind, or the like in which the parts are separable so that the stand may readily be carried from one position to another.

A further object of the invention is to provide a collapsible stand for supporting doors, window sash, blinds, and the like in which such articles are rigidly held and in which the stand is of a simple and economical construction.

With these and other objects and advantages in view the invention embodies an elongated beam having transversely disposed rails at the ends with knobs or resilient material on lower ends of posts at the ends of the rails and also at points on the beam and with door positioning and clamping elements carried by posts extended upwardly from the beam and also with a tool retaining shelf carried by upwardly extended posts at the rear ends of the transversely disposed rails.

Other features and advantages of the invention will appear from the following description taken in connection with the drawings, wherein:

FIGURE 1 is a front elevational view of the improved door, window sash, and blind holding buck with parts of the shelf at the rear thereof broken away showing a hinge connection in the intermediate part thereof.

FIGURE 2 is a cross section through the buck taken on line 2—2 of FIGURE 1 showing the door holding and positioning means at the left hand end of the buck.

FIGURE 3 is a cross section through the buck taken on line 3—3 of FIGURE 1 showing a slidable door positioning element carried by an arm extended from a

2

cross member spaced from the right hand end of the buck.

FIGURE 4 is a plan view of the improved door, window sash and blind supporting buck with parts broken away particularly to show the mounting of the slidable door positioning element at the right hand end of the buck.

FIGURE 5 is a cross section through a door gripping clamp taken on line 5—5 of FIGURE 1 with the parts shown on an enlarged scale illustrating, in particular, the screw with the right and left hand threads for bringing the gripping jaws against side surfaces of a door or the like.

FIGURE 6 is a cross section through the buck taken on line 6—6 of FIGURE 1 showing a post for supporting the arm on which the slidable door positioning element is mounted.

FIGURE 7 is a cross section taken on line 7—7 of FIGURE 1 showing the mounting of the transversely disposed rail at the right hand end of the buck and also illustrating the support for one end of a shelf at the rear of the buck.

FIGURE 8 is a longitudinal section through the clamp for doors, window sash, blinds, and the like taken on line 8—8 of FIGURE 4.

FIGURE 9 is a sectional plan taken on line 9—9 of FIGURE 1 also showing the mounting of the slidable door positioning element at the right hand end of the buck.

30 Referring now to the drawings wherein like reference characters denote corresponding parts the improved door, window sash, and blind supporting buck of this invention includes a horizontally disposed longitudinally positioned beam including sections 10 and 11, transversely disposed rails 12 and 13 connected to opposite ends of the sections 10 and 11 of the beam, a clamp supporting post 14 extended upwardly from the section 10 of the beam and having gripping jaws 15 and 16 slidably mounted on bars 17 and 18 adjustably mounted on the post 14 and actuated by a screw 19 having a right hand thread 20 on one section and a left hand thread 21 on the opposite section, a substantially V-shaped guide 22 with a deflecting plate 23 on the lower surface also mounted on the post 14, a positioning element 24 having enlargements 25 and 26 at the ends carried by an arm 27 slidably mounted on a post 28 which is connected to the beam section 11 as later described, knobs 29 of resilient material positioned on lower ends of vertically disposed posts, and a shelf including sections 30 and 31 connected by a hinge 32 and retained in a horizontal position by a pin 33, and the shelf is supported by extensions 34 and 35 extended upwardly from posts 36 and 37 at the rear ends of the rails 12 and 13.

55 In the drawings the parts are illustrated as being formed of pipe or tubing and connected with conventional fittings however, it is understood that the parts may be connected by other means, such as by welding and instead of the pipe or tubing bars, rods, or other conventional structural shapes may be used. In the design shown the inner ends of the sections 10 and 11 of the horizontal longitudinally disposed beam are connected by a T 38 and the extended end of the section 10 is threaded into a T 39, the opposite end of which is connected by a tube 40 to a T 41 at the forward end of the end rail 12 and the forward end of the T 41 is connected by a nipple 42 to an L 43 from the lower end of which a post 44 extends. One of the knobs 29 is positioned on the lower end of the post. The opposite end of the rail 12, which is positioned at the rear of the buck is threaded into a T 45 which connects the posts 34 and 36, as shown in FIGURE 2. The hub 46 of the branch connection of the T 45 is provided with openings 47 through which a pin 48 extends and with the

pin extended through similar openings in the end of the rail 12 the parts are retained in assembled relation. The pin 48 is connected to the lower part of the fitting 45 by a chain 49 to prevent accidental displacement of the pin. The upper end of the post 34 is provided with a bracket 50 to which the section 30 of the shelf is secured by screws 51.

The extended end of the section 11 of the longitudinally disposed beam is connected to a T 52, from which the end rail 13 extends and the forward side of the T is connected to an L 53 by a nipple 54. The L 53 is mounted on the upper end of a post 55 on the lower end of which one of the knobs 29 is positioned. The rail 13 is secured in a branch connection 56 of a T 57 by a pin 58 that extends through openings in the branch connection and rail 13 and the pin is secured to the buck by a chain 59 which prevents accidental displacement thereof. The upper end of the post 35 which extends upwardly from the fitting 57 is provided with a bracket 60, similar to the bracket 50, and the bracket 60 is secured to the section 31 of the shelf by screws 61.

The post 14, which extends upwardly from the T 39 at the end of the section 10 of the longitudinally disposed beam of the buck is provided with a head 62 that is secured in adjusted positions on the post by a set screw 63 and, particularly as illustrated in FIGURE 5 the head includes spaced parallel pins 17 and 18 with an arm 64 extended from the hub. Shanks 65 and 66 of the jaws 15 and 16, respectively are slidably mounted on the pins 17 and 18 and intermediate parts of the shanks are threaded on the right and left hand sections 20 and 21 of the screw 19. The intermediate part of the screw is provided with an annular recess 67 that is positioned between collars 68 and 69 and that is also positioned to receive a pin 70 that forms a key preventing longitudinal movement of the screw.

The door guide member 22 having the V-shaped opening 72 therein is adjustably mounted on the post 14 by a set screw 73 and the member is retained in adjusted positions by a pin 74 extended through side portions of the member 22 and openings 75 in the post 14, as shown in FIGURE 4. The pin 74 is secured to the fitting 39 by a chain 76 to prevent accidental displacement thereof. The member 22 is, therefore, adjustable vertically to correspond with the size of a door or the like and with the lower edge of the door positioned in the V-shaped slot 72 the upper part is placed between the jaws 15 and 16 and the screw 19 rotated by the pin 77 that extends through the head thereof whereby the clamping jaws are moved into gripping relation with side surfaces of the door. The right and left hand threads on the screw 19 make it possible to move both jaws toward or away from the surface of the door with each jaw moving the same distance from the center.

The opposite end of the door rests upon the member 24 which is secured by a pin 78 to the end of the arm 27 and the pin is connected to the end of a bar 79 by a chain 80 which prevents accidental displacement thereof.

The arm 27 is slidably mounted in a block 81, being retained in adjusted positions in the block by a set screw 82 and the block is retained in adjusted positions on the post 28 by a set screw 83. The block is retained in adjusted positions by a pin 84 that extends through spaced openings 85 in the post 28 and also through openings in the sides of the block 81 whereby the arm 27 and the door positioning element 24 may be set in suitable positions to correspond with the V-shaped slots 72 in the member 22 and the jaws 15 and 16 of the clamp on the post 14. The pin 84 is connected to the bar 79 by a chain 86 to prevent accidental displacement thereof.

The extended end of the bar 79 is provided with a socket 87 through which the section 11 of the longitudinally disposed beam extends and the bar is retained in adjusted positions on the beam by a set screw 88. The extended end of the bar 79 is also provided with a threaded socket 89 in which the upper end of a post 90

is positioned and, as shown in FIGURE 6, the lower end of the post is provided with one of the knobs 29.

The slideable or laterally adjustable member 24 is mounted to be aligned with the V-shaped socket 72 and a medial line between the jaws 15 and 16. The jaws 15 and 16 and the V-shaped slot 72 are retained in alignment by a continuous slot 91 in the post 14 upon which the members 22 and 62 are mounted, tips 92 and 93 of the set screws 63 and 73 being positioned in the slot.

The intermediate part of the longitudinally disposed beam including the sections 10 and 11 is supported by a medial post 94 that is secured in the T 38 and the lower end of the post is provided with one of the knobs 29.

The sections 30 and 31 of the shelf are mounted on the upper ends of the posts at the rear of the buck by the brackets 50 and 60, and as shown particularly in FIGURES 2 and 3 the upper surfaces of the sections of the shelf are provided with recesses 95 and 96 and beads 97 and 98 are positioned at the sides of the sections. As shown in FIGURE 4 the section 31 is provided with a tongue 99 and the tongue is positioned in a recess 100 of the section 30 with the parts in extended positions, as shown in FIGURES 1 and 4. The parts are connected by the hinge 32 and the pin 33, which extends through the tongue 99 and sections of the part 30 at the sides of the tongue retains the shelf in extended positions.

The pin 33 is connected by a chain 101 to an eye 103 on the under surface of the section 30 to prevent accidental displacement of the pin.

Operation

With the parts assembled, particularly as illustrated in FIGURES 1 and 4 a door, as indicated by the broken lines 102 is positioned in the buck with one end of the door on the member 24 and between the enlargements 25 and 26 and with the opposite end in the V-shaped slot 72 and on the deflecting plate 23. With the door in this position the screw 19 is rotated drawing the clamps 15 and 16, the gripping surfaces of which may be coated with pads of felt or other suitable resilient material, inwardly against the surfaces of the door whereby the door is rigidly held in an upright position so that recesses for hinge plates, door locks, and the like may be cut in the door with the upper edge of the door in a convenient position to be worked on. The elevation of the door is adjustable to compensate for the width of the door and the height of the carpenter or mechanic and the enlargements 25 and 26 on the member 24 are spaced to receive doors of varying thicknesses, the member 24 is reversed on the arm 27 to correspond with the thickness of a door by removing the lock pin 78 and resetting the elements.

The buck or bench holds doors, blinds, window sash, window and door frames, door jambs and other objects or devices in correct positions whereby such objects or devices may be worked on with electric jointers or planes. The bench or stand is set to the correct position by properly adjusting the mechanism, such as the parts 22 and 81 whereby the device may be adjusted to permit jointing larger objects or devices.

With the parts assembled as shown and described it will be understood that the buck may be divided into sections and readily carried in a tool box or bag to facilitate transportation from the residence of the carpenter to the job or from one job to another.

The parts are readily set up for use and the positions of the parts may be quickly adjusted to compensate for different articles whereby the device is designed for doors, window sash, blinds, and the like.

It will be understood that modifications, within the scope of the appended claims, may be made in the design and arrangement of the parts without departing from the spirit of the invention.

What is claimed is:

1. A buck for use in supporting doors, window sash, and blinds in positions for cutting recesses for hinge plates

and locks comprising a longitudinally disposed beam, transversely disposed rails connected to the ends of the beam, posts depending from the beam and the rails, a first post extended upwardly from the beam and spaced inwardly from one end thereof, a door rest positioned on the lower part of the post extended upwardly from the beam, a clamp above said rest for retaining a door in an upright position with the lower edge of one end thereof positioned upon the rest on the lower part of said post, another rest spaced inwardly from the opposite end of the buck and positioned to receive the lower edge of the other end of a door, a pair of parallel vertically disposed posts extending upwardly from the ends of said rails, a bracket on the upper ends of each of said vertically disposed posts, and a horizontally disposed longitudinally positioned foldable shelf mounted on the brackets at the upper ends of the vertically disposed posts at the rear portion of the buck.

2. In a buck for mortising doors, window sash, and blinds, the combination which comprises a longitudinally disposed beam, transversely disposed rails removably mounted on the ends of the beam, vertically disposed posts depending from the beam and from the rear ends of the rails, knobs of resilient material on the lower

ends of the posts, the posts at the rear ends of the rails having vertically disposed extensions extended upwardly therefrom, brackets telescopically mounted in said extensions for vertical adjustable movement in relation to said rails, a foldable shelf mounted on the brackets at the upper ends of said extensions, a post mounted on and extended upwardly from the beam near one end thereof, a door rest adjustably mounted on the lower part of the post extended upwardly from the beam, door gripping jaws above said rest also adjustably mounted on the post extended upwardly from the beam and positioned to grip the side surfaces of a door positioned on said rest, and a support near the other end of the beam and mounted for lateral movement with respect to the beam.
